UNITED STATES PATENT OFFICE.

SIMON DANCYGER, OF DAYTON, OHIO.

DISPLAY-FRAME.

SPECIFICATION forming part of Letters Patent No. 363,369, dated May 24, 1887.

Application filed April 8, 1885. Serial No. 161,565. (No model.)

To all whom it may concern:

Be it known that I, SIMON DANCYGER, a citizen of the United States, residing at Dayton, in the county of Montgomery and State of Ohio, 5 have invented a certain new and useful Improvement in Display-Racks; and I do hereby declare that the following is a full, clear, and exact description of the invention, which will enable others skilled in the art to which it applies to make and use the same, reference being had to the accompanying drawings, and to the letters of reference marked thereon, which form a part of this specification.

My invention relates to improvements in 15 display-racks for the exhibition of dry goods or other merchandise; and it consists of a frame with three longitudinal rods mounted on standards, so as to admit of a partially rotary movement, said frame being supported on 20 pivotal screws.

The object is to display the goods suspended thereon, and add to the attractiveness of the same by occasionally changing the relative position of the same.

25 I attain the object by the mechanism illustrated in the accompanying drawings, in which—

Figure I is a side view of the display-rack. Fig. II is a view of the display-frame. 30 A A are standards having plates O screwed onto the lower ends, and which plates have holes for wood-screws to fasten said plates to a counter, walls of a room, or ceiling. On the upper ends are attached elbow-joints, which 35 receive the threaded pivots G of the display-frame.

The display-frame consists of three parallel rods, the central one of which may be dispensed with, fastened together at their ends, and are all supported on the T-joints F, into 40 which are screwed the aforesaid threaded pivots which unite the said frame and standards. Upon the rods B, C, and D of the display-frame are suspended the goods to be exhibited, and as this frame admits of a movement 45 on its pivots, the position relatively may be changed at pleasure. The pivots are provided with right and left threads. These hold the frame securely to the standards and admit of the movement requisite to relatively change 50 the position of the goods suspended from the frame.

The frame may be placed in a horizontal or vertical position, or at any angle between these two positions.

Having fully described my invention, what I desire to secure by Letters Patent is—

A display-rack comprising standards with their bases and angular couplings, and the tubular shelf or frame having the right and 60 left screw-threaded journals for engagement with said angular couplings, whereby said journals are turned home, said standards and shelf forming a rigid homogeneous structure, substantially as set forth.

In testimony that I claim the foregoing as my own I affix my signature in presence of two witnesses.

SIMON DANCYGER.
